BURIAL CASKET CONSTRUCTION

Charles H. Votey, Scarsdale, N. Y., assignor to
 New York & Brooklyn Casket Co., Brooklyn,
 N. Y., a corporation of New York

Application May 15, 1947, Serial No. 748,232

3 Claims. (Cl. 27—2)

1

Wooden caskets are usually built of bottom, side and end wall boards fastened together by nails or screws. As these elements frequently work loose, it is the object of the present invention to reinforce the connection and to fasten the parts together more safely and securely.

The accompanying drawings illustrate one form of my invention.

Fig. 1 is a transverse sectional view of the frame work of a casket on a small scale.

Fig. 2 is an exploded perspective view showing cross sections of the principal parts of the construction on a larger scale.

The bottom of the casket is usually formed of transverse boards 4 and the sides and ends by boards 5. Along the sides the casket is reinforced by strips 6 and 7. The sides are secured to the bottom by longitudinal sheet metal channel members 8 and screws 9. Each channel member has a flange 10 which fits in a slot 11 in the side wall 5 and a flange 12 which fits in a groove 13 in the outer edge of the bottom member 4. Strip 7 has a groove 14 which accommodates the upper edge of the channel member 8.

Members 6 and 7 are shaped on a molding machine and glued together along the surfaces 15 and 16 and glued to the outer surface of wall 5 along the surfaces 17 and 18, respectively.

I also provide screws 19 which pass through the wall 5 from the inside and into the strip 6 between the surfaces 17 and 18 so as to strengthen the connections and prevent the upper flange 10 of the channel member from escaping from the slot 11.

The strip 6 not only ornaments the lower edge of the casket but furnishes a convenient hand rail for carrying the casket.

It will be understood of course that the end section of the casket (not shown) is the same as the side section herein shown.

I claim:

1. A burial casket having bottom and side walls connected by channel-like sheet metal members

2

each having a lower flange beneath an outer edge of the bottom wall and an upper flange let into a slot along the adjacent side wall and a side rail member having an upper part overlapping the upper edge of the channel-like member and secured to the side wall by screws above said upper edge and having a lower part spaced from the side wall for serving as a handle.

2. A burial casket having bottom and side walls connected by channel-like sheet metal members each having a lower flange beneath an outer edge of the bottom wall and an upper flange let into a slot along the adjacent side wall and a side rail member overlapping the upper edge of the channel-like member, said side rail member consisting of a strip inclined outwardly from the side wall and an interposed strip and means connecting the inclined strip to the side wall above the interposed strip.

3. A burial casket having bottom and side walls connected by channel-like sheet metal members each having a lower flange beneath the outer edge of the bottom wall and an upper flange secured along the side wall and an outwardly inclined side rail member having an interposed strip overlapping the upper edge of each channel-like member and secured to the side wall above said upper edge.

CHARLES H. VOTNEY.
